ORCHARD HEATING APPARATUS

James Birrell, Santa Barbara, Calif.

Application April 8, 1938, Serial No. 200,900

8 Claims. (Cl. 126—59.5)

This invention relates to orchard heating systems such as used in citrus fruit belts, and employing a number of liquid fuel burners spaced throughout the orchard. In accordance with the invention, means is provided for supplying atomized liquid fuel to the burners, and for collecting pools of the liquid at or in the vicinity of the burners, and for utilizing the pressure in the system to atomize the liquid fuel from the pools at the burners. This is most advantageous as compared with any system in which the fuel is pumped in liquid form under pressure to the burners through a liquid pressure line. If it is attempted to supply a liquid pumped under pressure to fuel burners, it is very difficult to regulate the burners, and practically impossible to attain efficient combustion of the fuel without employing atomizing air at the burners. But to supply compressed air for atomizing the fuel at the burners requires two pipe systems—one for air and one for the liquid fuel. Furthermore, in a pipe system in which the liquid fuel is pumped through as a liquid, the particular location of a burner at an elevation, on a hill for example, or below a hill at a low elevation, gives rise to troubles in effecting regulation at each burner, and makes it practically impossible to operate such a system satisfactorily.

In my system, although I employ header pipes or mains in which the fuel and compressed air flow respectively, I carry the fuel in a single line—an air pipe line, directly to the burners. Consequently there is only one valve to control at each burner to regulate the operation of the burner. Substantially perfect combustion is obtained because the fuel becomes thoroughly mixed with the air that carries it through the piping loops or laterals supplying the burners, and any excess of fuel supplied flows back to the supply point. In this way I greatly reduce the length of piping required and attain quite perfect combustion of the fuel at the burners. This is important, because if substantially perfect combustion is not attained, soot is formed which settles on the leaves of the trees, to their injury, or it may subject the orchard owner to action for damages for injury to lace curtains or other household goods of persons living in the vicinity of the orchard.

One of the objects of the invention is to provide apparatus of this kind so constructed so as to enable the burners to be operated with substantial uniformity; in other words, so that in the operation of the system substantially the same amount of heat units can be developed at the different burners.

In the preferred form of the apparatus, it includes a plurality of lateral conduits along which the burners are spaced; and one of the objects of the invention is to provide means whereby the fuel burning conditions in the different lateral conduits, will be substantially uniform, and so that the fuel supplied and consumed at the different burners of each lateral conduit, will be substantially the same for each burner in that lateral conduit.

A further object of the invention is to provide an efficient apparatus for effecting the advance of atomized fuel to burners through a pipe system, and to provide means whereby a local supply, or pool, will be developed adjacent each burner from which the liquid fuel may be drawn, and atomized through the agency of the pressure existing in the pipe system.

In the preferred embodiment of the invention, the apparatus includes lateral conduits along which the burners are spaced, and these laterals deliver into a return conduit, which returns unconsumed vapor and liquid fuel that has moved past the burners; and one of the objects of the invention is to provide means for maintaining a reduced pressure in the return conduit that returns the unconsumed fuel in the form of vapor and/or liquid, back to the supply container or reservoir.

A further object of the invention is to maintain a highly aerated condition of the liquid fuel in the supply reservoir, enabling a heavy oil to be employed.

Further objects of the invention will appear hereinafter.

The invention consists in the novel parts and combination of parts to be described hereinafter, all of which contribute to produce an efficient orchard heating apparatus.

A preferred embodiment of the invention is described in the following specification, while the broad scope of the invention is pointed out in the appended claims.

In the drawing:

Fig. 1 is a diagrammatic view illustrating the apparatus embodying my invention, and in which my method may be practiced, and showing the same as applied to two lateral conduits.

Fig. 2 is a vertical section upon an enlarged scale through one of the orchard heaters, and indicating portions of the lateral conduit, or lateral pipe loop, in which the same is connected. This view illustrates means for collecting a local pool of the liquid fuel to be atomized in the burner.

Fig. 3 is a vertical section through the burner in the same plane as in Fig. 2, but upon an enlarged scale, and further illustrating details of the burner.

5 Fig. 4 is a plan and partial section of the means employed in connection with each lateral conduit for effecting atomization of the liquid fuel at the entrance to the lateral conduit.

10 Fig. 5 is a vertical section showing the base of a burner and connections in the lateral conduit, with means for facilitating the development of the pool of the liquid fuel below the burner. This is a modification of the type of fuel collector pot illustrated at the bottom of Fig. 2.

15 Fig. 6 is a vertical section taken about on the line 6—6 of Fig. 5, and further illustrating the details of this pool collecting device.

20 Before proceeding to a more detailed description of the invention, it should be stated that in the preferred embodiment of the invention, I provide a compressed air conduit and a liquid fuel conduit, which preferably extend side by side through the orchard. To these conduits lateral conduits are connected, along which the fuel 25 burners or orchard heaters are spaced. Corresponding to each lateral conduit, I provide means for utilizing the compressed air for atomizing or vaporizing a quantity of the liquid fuel and for advancing the same through the lateral 30 conduit to supply the burners. In the vicinity of each burner, suitable means is provided for effecting the collection of a pool or local reservoir, or local supply of the liquid fuel corresponding to each burner, and at these points the 35 pressure existing in the system is utilized to atomize the fuel from the local supply. While it would be possible to employ at each burner compressed air unsaturated with the fuel, for atomizing the fuel from the local supply at the burner, I prefer to utilize compressed air super-saturated 40 with the liquid fuel through the medium of atomization effected at the inlet end of the lateral conduit. One of the advantages of this is that the super-saturated vapor being under pressure, facilitates the condensation and collection of the 45 liquid fuel at the local pools which supply the different burners. The different piping "loops" or lateral conduits, deliver to a return conduit or main, and at the point of connection to this main, regulator valves are provided which enable 50 sufficient pressure to be maintained in the different lateral conduits to insure efficient operation of the burners; that is to say, sufficient pressure in the compressed vapor in the conduit adjacent the burner. In order to prevent building up too 55 much back pressure in the return main, which might interfere with the free operation of the device, I provide means for maintaining a relatively low pressure in the return main. In this way, a proper differential of pressure is maintained between the return main and each lateral 60 conduit.

In addition to this, I also provide means for assisting in maintaining this effect, and at the same time, effecting a thorough aeration of the liquid fuel in the supply reservoir from which the system receives its liquid fuel.

65 As illustrated in Fig. 1, 1 indicates a supply reservoir or sump from which the liquid fuel is withdrawn by a pipe 2 that leads to a pump 3 that develops pressure in the liquid supply main, or conduit 4. The pump 3 may be driven by any kind of a motor 4', the shaft 5 of which may, if desired, be connected by a coupling 6 to a shaft 75 7 of another motor such as a motor 8 that drives

an air compressor, or blower 9, having an air intake 10 for atmospheric air, and delivering to an accumulator, or air reservoir 11, which contains air under any desired pressure controlled by a relief valve 12. From the air reservoir 11 the 5 pipe main, or conduit 13, leads off and preferably parallels the extension 4a of the fuel conduit 4. In other words, I prefer to provide an extension 13a of the compressed air line 13 that substantially parallels the extension 4a. These two 10 mains 4a and 13a in practice, would be of any length desired to provide for the operation of any necessary number of lateral conduits. In the present instance, however, I have illustrated two duplex lateral conduits comprising a lateral conduit 14a at the right, and another lateral conduit 14b at the left.

Means is provided corresponding to each duplex lateral conduit, for supplying atomized liquid fuel to the same. Any suitable construction 20 may be employed for this purpose. In Fig. 4, however, I illustrate a simple construction for this means, involving the use of a nozzle 15, the rear end of which is connected through a hand-operated valve 16 to the fuel conduit extension 25 4a. This nozzle 15 extends completely through the union or T-connection 17 that connects sections of the pipe line 13a and delivers compressed air within a pipe 18 that connects to the T-connection 17, leaving an annular passage 19 30 through which air will pass from the supply main 13a and into the lateral or loop 14a. A control valve 19' for hand-control, is preferably provided in the pipe 18 (see Fig. 1). This valve enables the supply to the loop or lateral 14a to be controlled by hand. Adjacent the valve 19' a branch pipe connection 20 leads off from pipe 18, which connection 20 is connected to the lateral conduit, or loop 14b. The return ends of these laterals 14a and 14b are connected through regulator valves 21 to a return conduit 22, the outer end of which is closed by a cap 23. These regulator valves 21 maintain the desired working pressure in the laterals. Any suitable type of regulator valve can be employed for this purpose, which will open and permit a flow of the vapor under 45 pressure into the return line 22. In order to prevent building up pressure in the return pipe 22, I prefer to utilize compressed air from the main 13a. For this purpose I provide a pipe connection 23' corresponding to each duplex lateral, and having a Pitot tube 24 that is bent in the direction of return flow in the pipe 22, which is indicated by the arrow on this pipe in Fig. 1. It will be evident that this jet of compressed air flowing in this direction and controlled by a valve 25 in the pipe connection 23', will produce a partial vacuum back of it, and induce flow of liquid or vapor passing into this line through the regulator valves 21. In Fig. 1 I illustrate a second duplex lateral or loop involving the single lateral conduits 14c and 14d that correspond respectively, to the laterals 14a and 14b. These laterals 14c and 14d are duplicates of laterals 14a and 14b, with all their accessories and valves, and 65 hence it will be unnecessary to describe the same.

The return pipe 22 extends back to the supply reservoir 1, and in order to facilitate the flow back to this reservoir, and also to aerate the fuel 1a in the reservoir 1, I prefer to provide means for projecting an air jet in the interior of this pipe in the direction of the return flow. For this purpose I employ an air nozzle 26, which may be supplied with compressed air through a pipe connection 27 leading over from the air line 70 75 75

13. The flow of air in the air line 13 and in the connection 27, may be controlled by a valve 28. A valve 29 is preferably provided in the fuel feed line 2 leading from the reservoir 1 to the pump 3.

5 Referring to Fig. 1, the heaters 30 are connected in series into the lateral conduits 14a and 14b. Any suitable type of burner may be employed with this system, but in Fig. 2 I illustrate a type of heater and burner that I prefer to employ. At a point adjacent to that at which the heater is to be located, I provide means in the lateral piping that will operate to effect an accumulation of the fuel. The illustration in 10 Fig. 2 shows a fuel pot or local reservoir 31, which may rest on the ground, indicated by the ground line 32, and this fuel pot is connected with the line piping 14b at a slight distance above its bottom.

20 In the operation of the heater, when the mist which super-saturates the compressed air flowing in the lateral arrives at the pot 31, a considerable quantity of the liquid will become condensed so that there will always be a pool 33 of the liquid fuel in this reservoir. The fuel pot 31 has a gas-tight head 34 so that above the level of the liquid fuel 33 a pressure chamber 35 is formed. The pressure in this chamber is utilized to atomize the liquid fuel 33 at a burner 36, which, for convenience, may be located above and supported on the head 34. This burner may be of any suitable construction, but preferably is constructed integrally with a cap 37 that screws onto a neck 38 extending up from the head 34. 25 A liquid fuel inlet tube 39 has its inlet mouth 40 located below the level of the liquid 33, and delivers the liquid into an inlet duct or chamber 41 formed in the casing 42 of the burner. This burner 42 preferably includes a valve in the 30 form of a plug 43 with a threaded portion 44 mounted in the casing, so that the valve can be adjusted in or out by means of a handle or hand-wheel 45. The valve is formed with a substantially conical shoulder 46 that cooperates with the conical seat 47 to close off flow completely, 35 or to regulate the amount of flow. The plug 43 has a tip 48 of reduced diameter that fits freely in the reduced bore 49, and this tip has a tapering bleeder passage 50 that has its widest 40 end at the tip of the reduced portion 48. The further this plug 43 is opened the larger the effective opening 51 would be where the inner end of the passage 50 projects beyond the end of a counterbore 52 slightly larger in diameter 45 than the bore 49. With this arrangement it will be evident that a very nice regulation of the fuel may be attained. The counterbore 52 constitutes a mixing chamber, and into this bore the vapor under pressure from the upper part of the 50 pot 31 is admitted through an air passage 53. This passage 53 is preferably located slightly to one side so as to admit the air in a vertical plane substantially tangentially to the side of the counterbore 52. This produces a swirling motion in 55 the admitted air, and effects a thorough mixing with the liquid oil. The oil with the air then passes into an annular chamber 54 disposed around the plug 43, and this chamber connects with a delivery duct 55 extending up through the 60 nozzle 56 of the burner and through the perforation in its tip 57. The amount of air passing up the passage 53 can be nicely regulated by means of a set screw 53' threaded in the wall of the casing, and the inner end of which projects 65 into the passage 53.

Instead of providing a fuel pot of the general construction shown in Fig. 2, its function may be performed by a more or less rudimentary fuel pot, such as that illustrated in Figs. 5 and 6. This fuel pot 58 shown in Fig. 5, is of small diameter, and operates substantially as a coupling between sections of the tubing 59. In this fuel pot, or coupling 58, means is provided for baffling the flow of the mist passing through the pipes 59. This tends to increase condensation, 10 and also operates as a dam or baffle to retain a pool 60 of the liquid fuel. Into this pool the lower end of the fuel inlet tube 61 of the burner extends. The interior of the fuel pot above the liquid level, constitutes a pressure chamber 62, 15 which operates to force the liquid up the tube 60, and atomizes the same in the same manner as described in connection with Fig. 3.

Any suitable means may be employed for supplying the liquid fuel 1a to the reservoir 1; for 20 example, an elevated tank 63 provided with a delivery pipe 64 and a valve 65 through which the fuel will run by gravity into the reservoir 1.

The pipe connection 27 that leads the compressed air to the aerating nozzle 26 may be provided with a valve 26a for controlling the amount of air that is admitted through this nozzle. Beyond this nozzle the return pipe 22 has a downwardly extending delivery neck 66 that delivers the return flow from the system, and compressed air from the nozzle 26 near the bottom of the reservoir 1, so that this air and returned unconsumed fuel bubbles up through the liquid fuel 1a. As the air bubbles up through the liquid fuel 1a, it naturally produces a considerable aeration of 35 the fuel, which increases the facility with which the fuel can be formed into a mist by the mist-producing means illustrated in Fig. 4. Furthermore, the increased quantity of air carried in the liquid fuel is valuable, in that it reduces the 40 viscosity of the heavy oil, and this enables very heavy oils to be employed in this system, and burnt satisfactorily. These heavy oils are much less expensive than the lighter oils, and this fact is favorable to the operation of this system at 45 a very low cost.

In Fig. 1, of course, the small circles 67 diagrammatically indicate the position of trees in the orchard. Of course, in practice, the lateral conduits, 14a and 14b would be of a length to 50 adapt them to the lengths of rows of the orchard. In reading Fig. 1, it should, of course, be understood that this is merely diagrammatic, and the parts of the drawing are not in proportion, or 55 on any scale.

In the operation of the method and apparatus, the driving of the pump 3 and blower or compressor 9, operate to advance the liquid fuel and compressed air respectively, in their mains 4 and 13. At the location of the laterals 14a, 14b, 14c, 60 and 14d, the vaporizing or mist-producing apparatus illustrated in Fig. 4, or similar apparatus, is located, which utilizes the compressed air to carburet and mix with the liquid fuel and produce a mist or fuel vapor which passes through 65 the lateral piping and through the heaters such as the heaters 30. At each heater, or in its immediate vicinity, a pool 33 of the liquid fuel is developed due to the condensation of the liquid carried in the mist, and at the same time, 70 pressure is developed in the pressure chamber 35 above the surface of this liquid. The pressure in the pressure chamber 35 at each heater, therefore forces the liquid fuel up the fuel tube 39 and produces a thorough mixture 75

of the fuel and air, and atomizes the same through the delivery duct 55 of the nozzle 56 of each burner. The pressure in each lateral is sufficient to operate the nozzles efficiently, and is maintained through the agency of the regulator valves 21, which open under the pressure for which they are set to deliver the return flow from the system into the return pipe 22. The bent nozzles 24 corresponding to each double loop or lateral duct, operate to admit compressed air from the compressed air line 13a to maintain a low pressure in the return pipe 22. In this way a substantially uniform condition in the different laterals can be maintained. The general pressure 10 in the return line 22 can be controlled also to a large extent, by the air nozzle 26 located near the end of the return main 22 where the returned flow is delivered back into the supply reservoir 1.

20 Of course, the valve 16 will enable the quantity of fuel being formed into a mist at each lateral loop, to be nicely regulated.

It is understood that the embodiment of the invention described herein is only one of the 25 many embodiments this invention may take, and I do not wish to be limited in the practice of the invention, nor in the claims, to the particular embodiment set forth.

What I claim is:

- 30 1. In an orchard heating system, the combination of a compressed air conduit, a liquid fuel conduit, a plurality of lateral conduits with a plurality of burners spaced along the same, and connections between the air conduit, the fuel 35 conduit and the lateral conduits to form a mist of the liquid fuel passing through the lateral conduits, and past the burners in series.
2. In an orchard heating system, the combination of a compressed air conduit, a liquid fuel 40 conduit, a plurality of lateral conduits with a plurality of burners spaced along the same, a connection for each lateral conduit for forming a mist of the liquid fuel with compressed air from the compressed air conduit, and delivering the mist into the lateral conduits and past all of the 45 burners, means for maintaining pressure in the lateral conduits, means for collecting liquid fuel from the mist, adjacent the burners, and means for utilizing the pressure in the lateral conduits 50 to effect the burning of the said collected liquid at the burners.
3. In an orchard heating system, the combination of a compressed air conduit, a liquid fuel conduit, a plurality of lateral conduits with a 55 plurality of burners spaced along the same, a connection for each conduit for forming a mist of the liquid fuel with compressed air from the compressed air conduit, delivering the mist into the lateral conduits and past the burners, means 60 for maintaining pressure in the lateral conduits, means for collecting liquid fuel from the mist, adjacent the burners, means for utilizing the pressure in the lateral conduits to effect the burning of the said collected liquid at the burners, a 65 return conduit connected with the lateral conduits for returning the unconsumed mist and liquid fuel, regulator valves for regulating the pressure in the said lateral conduits, and means for maintaining a differential working pressure 70 between the pressure in the lateral conduits, and the pressure in the return conduit.
4. In an orchard heating system, the combination of a compressed air conduit, a liquid fuel conduit, a plurality of lateral conduits with a 75 plurality of burners spaced along the same, a

connection for each lateral conduit for forming a mist of the liquid fuel with compressed air from the compressed air conduit, delivering the mist into the lateral conduits and past the burners, means for maintaining pressure in the lateral conduits, means for collecting liquid fuel from the mist, adjacent the burners, means for utilizing the pressure in the lateral conduits to effect the burning of the said collected liquid at the burners, a return conduit connected with the lateral conduits for returning the unconsumed mist and liquid fuel, and means for admitting jets of compressed air from the compressed air conduit into the return conduit at a plurality of points and flowing in the direction of flow in the return 10 conduit.

5. In an orchard heating system, the combination of a compressed air conduit, a liquid fuel conduit, a plurality of lateral conduits with a plurality of burners spaced along the same, a connection for each lateral conduit for forming a mist of the liquid fuel with compressed air from the compressed air conduit, delivering the mist into the lateral conduits, means for maintaining pressure in the lateral conduits, means for collecting liquid fuel from the mist, adjacent the burners, means for utilizing the pressure in the lateral conduits to effect the burning of the said collected liquid at the burners, a return conduit connected with the lateral conduits for returning the unconsumed mist and liquid fuel, and means for admitting jets of compressed air from the compressed air conduit into the return conduit. 20

6. In an orchard heating system, the combination of a compressed air conduit, a liquid fuel 25 conduit, a plurality of lateral conduits with a plurality of burners spaced along the same, a connection for each lateral conduit for forming a mist of the liquid fuel with compressed air from the compressed air conduit, delivering the mist into the lateral conduits and past the burners, means for maintaining pressure in the lateral conduits, means for collecting liquid fuel from the mist, adjacent the burners, means for utilizing the pressure in the lateral conduits to feed 30 the said collected liquid to the burners, a return conduit connected with the lateral conduits for returning the unconsumed mist and liquid fuel, and means for admitting jets of compressed air from the compressed air conduit into the return conduit. 35

7. In an orchard heating system, the combination of a supply reservoir for the liquid fuel, a liquid fuel conduit supplied from the same, a compressed air conduit, a plurality of lateral conduits with a plurality of burners spaced along 40 the same, a connection to each lateral conduit for atomizing the liquid fuel into a mist with compressed air from the compressed air conduit and delivering the mist into the lateral conduits, a return conduit to which the lateral conduits 45 connect, regulator valves in the lateral conduits adjacent their points of connection to the return conduit for maintaining pressure in the lateral conduits, and means for admitting jets of compressed air from the compressed air conduit 50

into the return conduit at different points in the return conduit and flowing in the direction of the return flow of the mist and liquid, to maintain a regulable reduced pressure in the return conduit.

8. In an orchard heating system, the combination of a supply reservoir for the liquid fuel, a liquid fuel conduit supplied from the same, a compressed air conduit, a plurality of lateral conduits with a plurality of burners spaced along the same, a connection to each lateral conduit for atomizing the liquid fuel into a mist with compressed air from the compressed air conduit and delivering the mist into the lateral conduits,

a return conduit to which the lateral conduits connect, regulator valves in the lateral conduits adjacent their points of connection to the return conduit for maintaining pressure in the lateral conduits, means controlled at will for admitting jets of compressed air from the compressed air conduit into the return conduit in the direction of the return flow of the mist and liquid, to maintain a regulatable reduced pressure in the return conduit, and means for forcing air into the liquid fuel supply below the level thereof to aerate the same.

JAMES BIRRELL.
